UNITED STATES PATENT OFFICE

SIMON COOPER, OF BROOKLYN, NEW YORK

WRAPPING MACHINE

Application filed June 28, 1929. Serial No. 374,490.

The invention relates to wrapping and folding machines.

In accordance with the invention means are provided for advancing sheets of material through the machine. As the sheets are being advanced through the machine parts thereof are wrapped about substantially flat rectangular objects. The remaining portions of the sheets are loosely folded about strips or

10 sheets of different material.

The embodiment of the machine illustrated in the drawings and described in the following specification is particularly adapted to wrap and fold what are known as "sachets" 15 in the permanent hair waving industry. These sachets comprise a non-porous sheet of paper, which is perforated at one region. The perforated region and adjacent portions of the sheet are wrapped about a substantial- 20 ly square pad formed of a suitable fabric, previously impregnated with a solution adapted to induce a permanent set in the hair when the completed sachet is applied to the hair and heat is applied. The solution

25 has been absorbed by the pads and the pads allowed to dry before being wrapped. The pads are wrapped so that the perforated regions of the sheets lie adjacent one of the flat surfaces of the pads. A substantial portion 30 of the sheet extends beyond the wrapped pad and is folded. A strip of regenerated cellulose or other suitable substantially impervious material is inserted between the folds of the extended portion. Sachets of this gen-

35 eral type are illustrated in Patent 1,449,874, dated March 27, 1923. The body of the sachet being made of a substantially non-porous material and the strip of substantially impervious material being wrapped on the 40 sachet, the only escape for vapors generated when the sachet is wrapped about a tress of hair and heat applied will be through the perforated area of the sachet and the vapors will be projected through these perforations

45 in jets. However, as far as this invention is concerned, details of the article may be varied.

Heretofore the wrapping and folding of such sachets has been done entirely by hand. 50 It is necessary for one operator to form the

perforations in the sheets and another operator to cut the sheets of regenerated cellulose. The material is then brought to the operators doing the wrapping and folding, and the finished product taken away from these operators. With the hand work many inaccuracies follow; for instance, the perforated region may not be properly located on the sheet, or if properly located on the sheet the pads 55 may not be positioned in the proper relation to the perforated regions, the regenerated cellulose may not be properly positioned, or other folds not made in their right places.

The machine of the present invention perforates the sheets, wraps the pads, cuts and 60 inserts the sheets of regenerated cellulose, folds the extended or body parts of the main sheets loosely around the sheets of regenerated cellulose and glues the entire sachet securely together. A single machine will perform the work of a large number of hand operators in a much more efficient and accurate manner.

The machine is designed so that all parts 65 are easily accessible for cleaning or adjustment purposes, particularly those parts which come in contact with the glue or paste. The parts and movements are of simple construction, considering the work accomplished, so that the machine may be operated by girls or 70 other unskilled labor.

As previously stated, the embodiment of 75 the machine illustrated and described is for folding and wrapping sachets of the kind referred to, but with slight modifications the mechanism may be utilized for folding and wrapping numerous other articles.

The many advantages of the machine will 80 become apparent as this specification proceeds.

Referring to the drawings forming a part 85 thereof and in which a preferred embodiment of the machine is illustrated:

Fig. 1 is a side elevation, part of the table at the feeding end of the machine being broken away for economy of space and part of the drive at the opposite or delivery end being broken away for similar reasons;

Fig. 2 is a plan view of the feed end of the 90 machine:

- Fig. 3 is a plan view of the intermediate part of the machine, this view being a continuation of Fig. 2 from the broken line indicated at the left-hand end of Fig. 2;
- Fig. 4 is a plan view of the delivery end of the machine and is a continuation from the broken line indicated at the left-hand end of Fig. 3. Figs. 2, 3 and 4 together may be considered as a plan view of the machine;
- Fig. 5 is a cross-sectional view on line 5—5 of Fig. 2;
- Fig. 6 is a fragmentary detail longitudinal sectional view on the line 6—6 of Fig. 5. This view is on a larger scale and particularly shows the perforating mechanism;
- Fig. 7 is a cross-sectional view taken on the line 7—7 of Fig. 3;
- Fig. 8 is a fragmentary detail sectional view, on a larger scale, taken on the line 8—8 of Fig. 3, and particularly illustrates the mechanism for making the first fold;
- Fig. 9 is a fragmentary detail sectional view taken on the line 9—9 of Fig. 2, showing the first or primary glue-applying mechanism;
- Figs. 10 and 11 are fragmentary detail sectional views taken on the lines 10—10 and 11—11, respectively, of Fig. 9;
- Fig. 12 is a fragmentary plan view of the mechanism at the feed end of the machine for properly positioning the sheets as they are entered into the machine. In this view the table which supports the sheets in their travel through the machine is omitted;
- Fig. 13 is a sectional view, taken on the line 13—13 of Fig. 3, and shows the operating mechanism for making the second and third folds;
- Fig. 14 is a fragmentary detail sectional view on a larger scale and looking in the opposite direction to Fig. 13. This section is taken on the line 14—14 of Fig. 29;
- Fig. 15 is a sectional bottom plan view taken on line 15—15 of Fig. 14;
- Fig. 16 is a fragmentary sectional view taken on an irregular line 16—16 of Fig. 3, and illustrates part of the mechanism for handling the pads;
- Fig. 17 is a fragmentary sectional view taken on the line 17—17 of Fig. 3 and shows parts of the mechanism for feeding the pads;
- Figs. 18 to 23 inclusive are diagrammatic views illustrating how the second and third folds are made and the pad positioned and enclosed by said folds;
- Fig. 24 is a detail sectional view of the magazine for the supply of pads and the mechanism for positioning the pads, this section being taken on the line 24—24 of Fig. 25;
- Fig. 25 is a sectional plan view taken on line 25—25 of Fig. 24;
- Fig. 26 is a detail sectional view taken at right angles to Fig. 24 and on line 26—26 of Fig. 25;
- Fig. 27 is a perspective view of the slide for ejecting the pads;
- Fig. 28 is a perspective view of the lower part of an adjustable gauge which controls the size of the opening through which the pads pass from their magazine;
- Fig. 29 is a fragmentary detail sectional view taken on the line 29—29 of Fig. 3;
- Fig. 30 is a fragmentary elevational view of some of the parts shown in Fig. 29 as they would appear in a different position;
- Fig. 31 is a detail sectional view of a pressing mechanism and means for holding the sheet or strip of cellophane while it is being cut;
- Fig. 32 is a detail sectional view of part of the pressing mechanism and is taken on line 32—32 of Fig. 29;
- Fig. 33 is a detail sectional view taken on line 33—33 of Fig. 32;
- Fig. 34 is a cross-sectional view taken on line 34—34 of Fig. 3;
- Fig. 35 is a central sectional view through the regenerated cellulose feeding mechanism;
- Fig. 36 is a detail sectional view taken on line 36—36 of Fig. 35;
- Fig. 37 is a fragmentary elevation on a larger scale of the means for separating the regenerated cellulose feed rollers;
- Fig. 38 is a cross-sectional view taken on line 38—38 of Fig. 3;
- Fig. 39 is a fragmentary detail elevation looking from the opposite side of Fig. 38;
- Fig. 40 is an edge view of two of the cams used to operate part of the mechanism for making the fourth and fifth folds;
- Figs. 41 and 42 show the face views of these cams and are sections taken on lines 41—41 and 42—42, respectively, of Fig. 40;
- Fig. 43 is a detail view, partly in section and partly in elevation, of an additional glue-applying mechanism, this view being taken on line 43—43 of Fig. 38;
- Fig. 44 is an elevation with parts in section on a larger scale and looking at the opposite side of the machine from Fig. 1. This view shows parts of the mechanism for making the fourth, fifth and sixth folds and the mechanism for applying a drop of glue to the sheet for holding the fifth fold in position;
- Figs. 45 to 49 inclusive show the mechanism for making the fourth and sixth folds in various positions during its operation;
- Fig. 50 is a detail sectional view taken on the line 50—50 of Fig. 48;
- Fig. 51 is a detail plan view of the mechanism for making the fourth and sixth folds in the position they assume in Fig. 48;
- Fig. 52 is a cross-sectional view taken on the line 52—52 of Fig. 3;
- Fig. 53 is a plan view of parts of the mechanism shown in Fig. 52 and is taken on the line 53—53 of Fig. 52;
- Fig. 54 is a detail sectional view taken on line 54—54 of Fig. 52;

Figs. 55 to 59 inclusive are schematic views illustrating different positions and the operation of the mechanism for making the fifth fold;

5 Fig. 60 is a fragmentary sectional view taken on the line 60—60 of Fig. 3;

Fig. 61 is a plan view, full size, of one of the grippers for the sheets;

10 Fig. 62 is an elevation of the gripper looking from the right of Fig. 61;

Fig. 63 is a sectional view of the gripper taken on line 63—63 of Fig. 61;

Fig. 64 is a detail sectional view taken on line 64—64 of Fig. 63;

15 Fig. 65 is a cross-sectional view taken on line 65—65 of Fig. 64;

Fig. 66 is a detail sectional view on a larger scale and is taken on line 66—66 of Fig. 4;

20 Fig. 67 is a plan view of one of the sheets;

Fig. 68 is a similar view after the perforations have been made;

Fig. 69 is a plan view of the sheet after the glue has been applied at the first or primary glue station;

25 Fig. 70 shows the sheet after the first fold has been completed;

Fig. 71 shows the pad in position;

Fig. 72 shows the sheet with the second or short fold made over the pad;

30 Fig. 73 shows the sheet with the third fold complete and enclosing the pad;

Fig. 74 shows the regenerated cellulose in position on the sheet;

Fig. 75 shows the fourth fold completed;

35 Fig. 76 shows the partially wrapped sachet with the glue applied at the second and third gluing stations;

Fig. 77 is a plan view of the sachet with the fifth fold completed;

40 Fig. 78 is a plan view of the finished sachet, the sixth or last fold having been made; and

Fig. 79 is a perspective view of the finished sachet.

45 Referring again to the drawings, all the mechanism is carried or supported on a main frame comprising longitudinal side members 1 and 2 and supporting legs 3. A table 4 running substantially the length of the frame and cut away at various places for the mechanisms hereinafter described is carried on cross members 5, which are mounted on the upper longitudinal side frame members 1 and in addition to supporting the table the members 5 which extend across the machine act as ties for the side frames. To avoid interference with some of the mechanisms, a number of the cross members are carried by only one side frame and extend only part way across the machine.

50 Mounted in bearings 6 secured to the lower longitudinal side members 2 is a shaft 7, see Fig. 65. The shaft 7 has a sprocket 8 secured thereto. Fixed with respect to said sprocket 8 is a four-tooth ratchet wheel 9. A pawl 10 adapted to engage the teeth of said

ratchet 9 is mounted on an arm 11, which in turn is freely mounted on shaft 7. A link 12 connects the arm 11 with a crank 13 on the constantly driven shaft 14. The parts just described are illustrated in Figs. 1, 4 and 70 65 and from an inspection of the drawings and foregoing description it will be apparent that they impart an intermittent movement to the sprocket 8.

The shaft 14 is mounted in suitable bearings at the end of the machine and is driven from a reduction gearing housed in casing 15, which in turn is driven from the motor 16 through the medium of pulleys 17 and 18 and belt 19. 75

The sprocket 8 intermittently drives a sprocket chain 20, which also engages idler sprockets 21 and 22. The upper run of the sprocket chain passing from sprocket 22 to sprocket 8 lies below the table 4 and is carried in guides 23, which are supported in the cross members 5. The table 4 is slotted longitudinally at 24 and grippers 25 secured at regular intervals to the chain pass through the slot 24 and carry the sheets of material 90 through the various mechanisms along the table. The grippers 25 are preferably secured to the sprocket chain 20 by a pair of the adjoining pins utilized to connect the links of the chain, as illustrated in Fig. 61. 95

Secured to one end of the shaft 14 is a skew gear 26, which meshes a skew gear 27 on a cam shaft 28 running longitudinally of the machine and carried by bearings 29 secured to the frame of the machine. This shaft is constantly rotated and carries a large number of the cams that operate the different mechanisms of the machine. 100

The opposite end of shaft 14 carries another skew gear 30, which meshes a skew gear 31 carried on a short shaft 32. The shaft 32 has a spur gear 33 on its end opposite the skew gear 31 (Figs. 4 and 65), which meshes a spur gear 34 on a central longitudinally extending cam shaft 35. This shaft is supported on bearings 36 extending between the side frame members 2, and is also constantly driven and carries a plurality of cams. 110

A gear 37 secured to shaft 35 engages a gear 38 on cam shaft 39. The cam shaft 39, see Figs. 44 and 65, is supported in bearings 40 secured to the frame member 2 and carries the cams for operating the cellophane feeding and cutting mechanism, hereinafter described. 115

120 Mounted in the frame at the feed end of the machine is a table 41, (see Figs. 1 and 2), at which the operator sits. This table 41 carries a trough 42 substantially the width of 125 the wrapper sheets to be fed into the machine. The operator has a stack of these sheets in front of her and feeds them into the machine one at a time. One of the sheets A is indicated in broken lines in Fig. 2 in the 130

position it assumes when fed into the machine by the operator.

The sheet or blank A is shown in full lines in Fig. 67. It is provided with a cut 43, which leaves a tab or flap 44. At right angles to cut 43 is a short cut 45. In line with the cut 45 is another longer cut 46. The cuts 43, 45 and 46 define another tab or flap 47, extending from the body 48 of the sheet.

10 Stops are provided against which the forward edge of the sheet A may be placed when entering the sheet into the machine. Automatic means are provided for bringing the stops up when the sprocket chain 8 and grippers are stationary and for removing the stops from the path of travel of the sheet when advanced by one of the grippers 25. This mechanism is particularly illustrated in Figs. 1, 2, 5 and 12.

20 The fingers 49 which act as the stops are formed integral with or mounted on a yoke 50, which is pivoted on a shaft 51 upon which the idler sprocket 22 is mounted. The yoke has pivoted to it a link 52, which is connected to a cam fork 53. The cam fork carries a roller 54, which engages a cam groove in a cam 55 secured to the cam shaft 35. The cam is so laid out that it will raise the stops 49 when the chain 8 is stationary and 30 permit the operator to properly position a sheet with its forward edge against the stops. At this time automatic means are provided for opening and closing the gripper jaws so that the sheet may be inserted between the 35 jaws and grasped.

This means is illustrated in Figs. 1, 2 and 5, and will now be described. Pivoted at 56 in a bracket secured to one of the side frames 1 is a lever 57. One end of this lever extends over the center of the machine and in one position rests above the movable jaw of one of the grippers when the gripper is stationary.

When this extending end of the lever 57 is 45 depressed, it contacts with said movable jaws and the gripper is opened and held open for a short period for the reception of the sheet A.

The opposite end of the lever 57 is pivoted at 58 to a cam fork 59. This cam fork 50 59 carries a cam roller 60 which engages a cam groove in a cam 61 secured on the cam shaft 28. The cam 61 is timed to depress the lever 57 and open the gripper immediately upon the machine coming to rest, and allows 55 the gripper to close and grasp the sheet just prior to the stops 49 being withdrawn.

Means are provided for forming a set of fine perforations B in the flap 47 of the sheet A, as shown in Fig. 68. The perforating 60 means also functions while the chain 20 and grippers 25 are stationary, and is particularly illustrated in Figs. 1, 2, 5 and 6.

The perforating means will now be described. A strong, rigid casting or bracket 65 62 is secured to one of the frame members 1.

Pivoted at 63 on an ear of the bracket 62 is a lever 64. One end of the lever 64 is pivoted at 65 to a slide 66 which may move up and down in a guideway in the bracket 62. Secured to the under side of an extension from the slide 66 is a plate 67 having a plurality of pins 68 fixed thereto. When the slide 66 is depressed these pins pass through the sheet A and enter a platen 69 mounted on an extension or enlargement 70 of one of the cross members 5 and form the series of fine perforations B in the sheet A.

A stripper frame 71 is carried on studs 72 slidably mounted in the slide 66. The stripper frame is normally forced away from the slide by springs 73 and its downward movement is limited by cross pins in the upper parts of the guide studs 72. After the perforations B have been made and the slide is being moved upward, the springs 73 will hold the sheet down until the pins 68 have been withdrawn from the sheet. If desired the stripper frame 71 may be provided with individual holes for each of the pins 68 so as to insure against the sheet being stretched or enlarged as the perforating pins 68 are withdrawn.

The opposite end of the lever 64 is pivoted at 74 to a cam fork 75. The cam fork 75 carries a cam roller 76 which engages a cam groove in a cam 77 secured to the cam shaft 28. The cam 77 is timed so as to operate the perforating mechanism while the chain 20 is at rest. The position of the sheet A while being perforated is indicated at *a* in Fig. 2.

While the sheet is moving from the perforating position *a* indicated in broken lines in Fig. 2, to its next position *b* in Fig. 2, strips of glue or paste are applied to the sheets. These strips of glue are indicated at C, D, E and F in Fig. 69. This glue-applying mechanism, which is particularly illustrated in Figs. 1, 2, 7, 9, 10 and 11, will now be described.

Secured to both side frames 1 are brackets 78. These brackets have sloping upper surfaces, to which plates 79 are bolted. A glue pot or container 80 having ribs or flanges 81 on its sides rests on the plates 80 and may slide in relation thereto, being prevented from moving away from the plates by bars 82 secured to plates 79 and having an overhang contacting with the ribs or flanges 81. The downward movement of the glue pot on the sloping plates 79 is limited by set screws 83 mounted in ears on the plates 78 and contacting with the ends of the flanges 81. These set screws are adjustable for a purpose hereinafter described.

The glue pot is firmly held in position by locking means contacting with the upper end of the ribs or flanges 81. The locks comprise arms 84, which are pivoted at 85 to ears or lugs on the plates 79. The arms 84 have extensions 86, which are provided with cam

surfaces to cooperate with the ends of the ribs 81 and openings in the plates 79. When it is desired to remove the glue pot for cleaning or replenishing the supply of glue, the arms 84 are raised and the glue pot is slid upwards and out of engagement with the members 82. Handles 87 are provided on the glue pot to facilitate handling the same.

The glue pot has an open compartment 88, which is fed from the main reservoir 89, through a plurality of comparatively small openings 90. Mounted on a shaft 91 extending across this open compartment 88 is a plurality of rollers 92. The outer peripheries 15 of these rollers engage segments 93 secured to a driven shaft 94, which is mounted in bearings 95 bolted to the side frames 1. The rollers 92 transfer the glue to the segments 93, which in turn transfer it to the sheet A.

It is desirable to have only a light contact 20 between the rollers 92 and segments 93. The set screws 83 are adjusted so as to obtain the desired contact. The set screws 83 also prevent the rollers 92 from being pushed against 25 the segments and causing irregularities in their peripheries. The periphery of the segments may be grooved, as indicated in Fig. 2, to cause a more even distribution of the glue.

Means are provided for controlling the 30 amount of glue to be transferred to the segments. A cross bar 96 extends across the open compartment above the rollers 92. Extending downwardly from the cross bar 96 alongside of each roller 92 is an L-shaped 35 scraper 97, the short leg of which may be adjusted toward or away from the roller 92 by a wing nut 98. The rollers 92 pass through openings in the front wall of the open compartment 88, and the amount of 40 glue passing through these openings and taken up by the rollers may be controlled by manipulating the wing nuts 98. It is important that the glue be maintained at a substantially even level in the open compartment 88 so as to provide for an even 45 distribution of the glue to the rollers 92 and thence to the segments 93. The main reservoir 89 acts as a hydrostatic glue well. When the level of the glue in compartment 80 falls below the top of the openings 90 a small amount of air will be permitted to enter the reservoir 89 and sufficient glue will 50 pass through said openings to maintain the desired even level, thus insuring an even distribution of glue to the segments 93 and permitting of an even application of the glue to 55 the sheet while it is in motion.

The segments 93 may be adjusted on the shaft 94 so as to distribute the glue where 60 desired. A greater or less number of segments may be employed. On a sheet of greater width it would be desirable to have more segments, so as to have more strips of glue and on a narrower sheet one or more of the segments might be eliminated.

It is desirable to drive the rollers 92 at the same peripheral speed as the segments and also that the peripheral speed of the segments be the same as the rate of speed of the sheet passing under the segments and to which the glue is being applied.

A shaft 99 is mounted below the table 4 in bearings on the side frame 1. This shaft 99 carries a sprocket 100 which engages the chain 20. As the speed of travel of the paper is controlled by the chain 20, the peripheral speed of sprocket 100 will be the same as the speed of the paper. A gear 101 is secured to the shaft 99 and meshes with a gear 102 of the same size secured to the segment shaft 94, thus driving the segments and causing their peripheral speed to be the same as that of the sheet being drawn beneath them.

Adjacent the gear 102 on the shaft 94 is another gear 103, which engages a spur gear 104 secured to a stub shaft 105 (Figs. 2 and 10). The stub shaft 105 is mounted in one of the bearings 95 and is in line with shaft 91, which carries the rollers 92. The shaft 105 drives the roller-carrying shaft 91 by a pin connection 106, shown in Figs. 2 and 10. The roller shaft 91 being geared to the segment shaft 94, the peripheral speed of the rollers 92 and segments 93 will be the same. The pin connection 106 permits the ready removal of the glue pot 80.

Openings 107 shown in Fig. 9 may be provided in the table 4 beneath the segments 93. The forward edge of these openings may be slightly raised, as indicated at 108 in Fig. 9, and the rear edge slightly depressed as shown at 109 in the same figure. This will cause a better contact of the sheet and the segments while the glue is being applied, and if there should be any slight irregularity due to the glue adhering and hardening on the segments, there will be no binding action on the sheets between the segments and table.

It is thought that from the foregoing the method of applying a plurality of strips of glue to the sheet will be plain. The method described and illustrated is a preferred form and has been extremely successful in practice, but numerous other methods could be devised for accomplishing the desired result and would be considered as coming within the spirit of the invention.

In the next position of the sheet, indicated at c in Fig. 3, and during the interval of rest, means are provided for folding the flap 44 back onto the body portion 48 of the sheet. The sheet after this first fold is completed is illustrated in Fig. 70. The two strips of glue E and F will hold the flap 44 to the body portion 48 of the sheet. The means for making this first fold is particularly illustrated in Figs. 3, 7 and 8 and will now be described.

Part of the table 4 is cut away as indicated at 110 in Fig. 3 and in this opening is mounted a swinging plate 111. When the sheet is be-

ing moved to the position *c* from the position *b* or away from the position *c* to the succeeding position, the plate 111 is flush with the table 4 and in effect acts as part of the table.

8 A gripper 112 is pivoted at 113 to an ear secured to the under side of the plate 111. When the sheet comes to rest in the position *c* this jaw or gripper 112 is open and immediately thereafter it closes and clamps the 10 free end of the flap 44 to the plate 111 and the plate 111 is rotated approximately 180° and deposits the flap 44 on the body portion 48 of the sheet. The gripper 112 is then opened and the plate 111 is moved back so as 15 to cover the opening 110.

The plate 111 is secured to a stud 114 which is mounted in a bearing 115 bolted to one of the side frames 1. Also secured to this stud 114 is a pinion 116, which engages a rack 117 20 mounted for vertical movement in the bearing 115. The lower end of the rack is pivoted to a link 118, which in turn is pivoted at 119 to a cam lever 120 (see Fig. 7). The opposite end of the cam lever is pivoted to a 25 bracket 121 secured to one of the lower side frame members 2. The cam lever 120 carries at its intermediate part a cam roller 122, which engages a cam groove in a cam 123 secured to the cam shaft 35. The cam 123 30 is so timed as to raise and lower the rack 117 and thus rotate the plate 111 at the proper time.

35 The means for opening and closing the gripper jaw 112 on the plate 111, for grasping and releasing the flap 44 at the proper times, will now be described. The gripper jaw 112 is formed on one end of a lever 124, which, as heretofore mentioned, is pivoted at 40 113. The lever 124 carries at the end opposite the jaw 112 a friction roller 125.

45 Mounted in bearings 126 bolted to the side frame 1 is a shaft 127 (see Figs. 3 and 8). This shaft has secured to it at one end a lever 128, which has a cam surface 129 on its outer 50 end. This cam surface 129 engages the roller 125 and holds the jaw 112 open until the sheet assumes position *c*. The cam surface 129 is then moved away from the roller 125 and the jaw 112 is forced by the spring 130 against the plate 111 and grips the paper.

55 Another lever 131 is secured to the opposite end of the shaft 127 and carries on its outer end a cam surface 132. After the plate 111 has been rotated 180° and the flap 44 has been deposited on the body portion 48 of the sheet, the cam surface 132 engages the roller 125 and opens the gripper 112, holding it open until it has cleared the sheet on its return movement, after which the cam surface 132 is moved out of contact with the roller 125 and the jaw closes and remains closed until the roller 125 again contacts with the cam surface 129 on lever 128.

60 The shaft 127 carries a cam lever 133 which has secured to its end a cam roller 134. The

cam roller 134 engages a groove in a cam 135, which is secured to the cam shaft 28. The cam 135 is so arranged that it will move the levers 128 and 131 so as to cause the cams 129 and 132 to coat with the roller 125 and open and close the gripper 112 at the proper times. A buffer spring 136 mounted in a fixed member 137, secured to the chain guide 23, engages the plate 111 or a bracket secured on its under side, as the plate is returned to its normal position. This spring acts as a shock absorber, thus adding to the life of the mechanism and helping to eliminate the noise of operation.

65 From the foregoing description and an inspection of the drawings the operation of the mechanism for making the first fold will be manifest. Numerous changes in details of construction and arrangements of parts may be made.

70 A number of operations are performed at the next station or position of the sheet, which is indicated at *d* in Fig. 3. The pad G is laid on the sheet over the perforations 13, the second and third folds of the sheet are made over the pad, the sheet of regenerated cellulose is laid on the body portion, and the first fold and body portion of the sheet and the sheet of regenerated cellulose are pressed or ironed.

75 As heretofore stated, Fig. 70 shows the sheet after the first fold has been completed. Fig. 71 shows the pad G in position over the perforations. The second fold is completed in Fig. 72. In Fig. 73 the sachet is shown with the third fold completed and the pad enclosed by these two folds, the strip of glue C holding these folds in their proper position. Fig. 74 shows the sheet of regenerated cellulose H in position and held there by the strip of glue D. This is the condition of the sachet as it leaves position *d* of Fig. 3.

80 The mechanism for positioning the pad G on the sheet will first be described. This mechanism is shown in a general way in Figs. 1 and 3 and illustrated in detail in Figs. 16 and 17 and Figs. 24 to 30 inclusive.

85 A magazine 138 is secured to a bracket 139, which is bolted to one of the side frames 1. The pads G are stacked up in the magazine 138 and are fed one at a time to the sheets A as they come to rest in position *d*. Slots 140 are cut in the sides of the magazine, so that the operator may at all times see if the pads are resting evenly against each other. The inner faces of the magazine are cut away, as indicated at 141, so that the pads only contact with the magazine at their corner portions and thus eliminate friction as they are traveling downwards.

90 The bottom of the magazine is closed by a slide 142 (Fig. 27), upon which the stack of pads rests. The rear part of the slide is thickened so as to form a shoulder 143, the length of the shoulder being a trifle less than 146

the thickness of a pad. The pads normally rest on the thin part of the slide, and when the slide is reciprocated in guides in the lower part of the magazine, the shoulder 143 will push or feed the lowermost pad from beneath the stack. This pad will be then projected beyond the magazine and will rest on the thin part of the slide, where it is grasped by other mechanism, hereinafter described, and positioned on the sheet.

The slide has a central slot 144, which accommodates a foot 145 for raising the stack of pads and thus preventing any of them being fed. In starting the machine, the foot 145 is raised so as not to feed any pads until a sheet has come to position d. In the operation of the machine the operator may occasionally miss feeding in a sheet. The foot 145 would then be raised if there were no sheet in position d. In this way wastage of the pads is saved and the probability of loose pads interfering with the operation of the machine is eliminated.

The foot 145 is formed on the lower end of a depending member pivoted at 146 to a lever 147, which is pivoted at 148 to the magazine. The lever 147 is provided with a handle 149, which in its raised position frictionally engages a slotted plate 150 secured to the magazine so as to hold the foot in its raised position until the handle 149 is depressed by the operator.

The slide 142 has a lug on its lower side and pivoted at 151 to the lug is a slide rod 152. The other end of the slide rod 152 is pivoted at 153 to a lever 154, which in turn is pivoted at 155 to a depending bracket 156 bolted to the side frame 1. The opposite end of the lever 154 is pivoted to an extension from a cam fork 157. This cam fork 157 carries a cam roller 158, which engages a slot in a cam 159, secured to the cam shaft. The cam 159, through the mechanism just described, will reciprocate the slide 142 so as to feed the pads B at the proper time. These parts are illustrated in detail in Fig. 17.

Means are provided for adjusting the size of the opening through which the pads are fed from the magazine. An adjusting plate 160 (see Fig. 28) is formed on the lower end of a slide 161. The slide 161 has a threaded ear 162 on its upper part, which is engaged by a screw 163. The screw 163 is mounted in an angle bracket 164 secured to the magazine and has a knurled head 165. The screw 163 may be rotated but is prevented from longitudinal movement. It will thus be apparent that by rotating the screw 163 the adjusting plate 160 may be raised or lowered so as to increase or decrease the size of the opening through which the pads pass from the magazine and thus insure only the lowermost pad being fed.

The means for grasping the pad after it has been projected from the magazine by the slide

142, and positioning it on the sheet will now be described. The slide 142 and pads B are shown in various positions of this operation in the schematic views of Figs. 18 to 23, which are made primarily to illustrate the operation of the second and third folding mechanisms.

A slide 166 is mounted for vertical reciprocation in guides 167 formed on the front of the magazine. The slide 166 has a foot 168 on its lower end. Mounted on pins 169 slideable in the foot 168 is a plate 170. The plate 170 is normally held away from the foot 168, as shown in Fig. 29, by springs 171. In Fig. 18 the plate 170 is shown in its upper position and the slide 142 is being projected. Immediately upon the slide 142 being fully projected, the plate 170 is carried down and onto the pad by the slide 166.

The foot 168 carries a pair of grippers 172, pivoted at 173. The grippers are pivoted at 174 to links 175, which are pivoted at 176 to the lower end of a slide rod 177. The slide rod 177 is mounted in ears 178 on the slide 166. A spring 179 on the slide rod is interposed between a collar 180 and the upper ear 178 of the slide 166. The spring 179 normally tends to force the slide rod 177 downwards and through the medium of links 175 causes the grippers 172 to move toward the lower face of the plate 170 and hold the pad G against said lower face. The springs 171 are forcing the plate 170 toward the grippers, and thus the pad will be firmly held between the grippers and the plate.

In Fig. 30 the plate 170 is pressed against the pad B and the grippers have been moved so as to firmly hold the pad against the plate. The slide 142 is then withdrawn and the pad is carried down toward the sheet. Fig. 19 shows the sheet A in place and the pad being carried down while held between the plate 170 and grippers 172.

After the pad has been deposited the grippers are withdrawn from underneath it and the plate 170 holds the pad in position until the second or short fold hereinafter described has been completed. In Fig. 20 the plate 170 is holding the pad in position and the second fold is partially made. In Fig. 21 the second fold has been completed and the plate 170 is shown as moving away from the pad. Fig. 29 shows an actual view of the parts in about the same position they assume in the diagrammatic view of Fig. 21.

Fig. 16 illustrates the mechanism for moving the slide 166 up and down and for moving the slide rod 177 in relation to the slide so as to operate the grippers 172 at the proper time. The slide 166 has a lateral extension 181, which carries a roller 182. This roller is engaged by the bifurcated end of a lever 183, which is pivoted at 184 to the magazine-supporting bracket 139. The opposite end of lever 183 is pivoted at 185 to an adjustable extension from a cam fork 186. This cam fork

186 carries a cam roller 187, which engages a cam groove in cam 188 secured to the cam shaft 28. This cam 188 is so timed as to raise and lower the slide 166 at the proper times.

Engaging the under side of the collar or member 180 secured to the slide rod 177 is a roller 189. The roller 189 is mounted on the end of a stud 190, which is secured to a lever 191, also pivoted at 184 to the magazine-supporting bracket 139. The other end of lever 191 is pivoted at 192 to an adjustable extension from a cam fork 193. The cam fork 193 carries a cam roller 194, which engages a cam groove in cam 195 secured to the cam shaft 28 adjacent the cam 188. The cam groove in cam 188 is so formed as to raise the slide rod 177 on slide 166 and operate the grippers 172 to open them at the proper time for releasing a pad and preparatory to grasping a pad.

It is thought from the foregoing that it will be clear how the pads are withdrawn from the magazine and positioned on the sheet. A preferred form of mechanism has been illustrated and described for performing this operation but many changes may be made in arrangements of parts or other suitable mechanism substituted for feeding the pads. In the embodiment of the machine illustrated and described, the objects being fed are pads. However, with minor changes in the mechanism, the objects might be solid or of even a more flexible nature than the pads and might be of widely varying thicknesses and shapes.

The mechanism for making the second and third folds will now be described. Parts of this mechanism are illustrated in Figs. 1, 3, 13, 14, 15, 24 and 29, and the operation of the folding mechanism is clearly illustrated in Figs. 18 to 23 inclusive.

When the folding mechanism is not in operation and the sheet A is being positioned over it or moved away from it, this mechanism rests below the table 4, as indicated in Figs. 18 and 19. Openings 196 are provided in the table through which the folding mechanism operates when in its raised position as shown in Figs. 20 to 23.

The folder for making the second or short fold is designated 197 and that for the third fold 198. These folders are mounted so that they may be raised and lowered and each rotated on its axis about 180°. They are mounted on shafts 199 and 200, which have bearings in a slide 201 mounted for vertical movement in a guide 202 formed in a bracket 203 bolted to one of the lower frame members 2.

The bearings for the shafts 199 and 200 are formed in ears on the upper part of the slide 201. Plates 204 are secured to the tops of these ears. When the folders are in their inoperative position below the table 4, the plates 204 are flush with the table and in effect form part of the table so as to provide adequate

support for the sheets as they are drawn along by the grippers 25.

The folder 197 is quarter round in cross-section and is secured to or formed as part of the shaft 199. The folder 198 is formed of three plates 205, 206 and 207. These plates are secured to pins 208, which are slidably mounted in a casting 209 secured to or forming part of the shaft 200. The plates are normally held away from the casting 209 by springs 210.

The operation of the folders will be described, particular reference being had to Figs. 18 to 23. Fig. 18, as previously mentioned, shows the folders in their lower or inoperative position. The slide 142 is projecting a pad G from the magazine and the plate 170 and grippers 172 are descending to grasp the pad. At this time one of the grippers 25 would have moved a sheet from position d to the next station and the following gripper 25 would be moving another sheet to position d.

In Fig. 19 the slide 142 has been withdrawn and the plate 170 and grippers 172 are carrying a pad G downwardly to position it on the sheet A, which now has been moved to position d by one of the grippers 25 and is at rest.

Fig. 20 shows the folders raised and in operation. Plate 170 has firmly held the pad G in position until the second or short fold has been completed and the folder 197 then holds the second fold down and maintains the position of the sheet and pad. The third folder has been rotated about 90° and holds this position until the plate 170 and parts carrying the same move out of the path of folder 198.

Fig. 22 shows the folder 198 as having completed the third fold. The folder 197 is now moving away. In Fig. 23 folder 197 is completely withdrawn and folder 198 partially withdrawn and the both folders have started their downward movement to return to the position of Fig. 18.

Folder 198 as previously stated comprises three plates 205, 206 and 207, yieldingly mounted in relation to casting 209. Referring to Figs. 29 and 73, it will be noted that these plates are so arranged that the central one 206 presses on the folds over the region where the pad is inserted. The short end plate 205 presses on the short part of the fold beyond the pad or away from the body portion 48 of the sheet. The remaining plate 207 presses on that part of the fold adjacent the body portion. As the plates are all separately mounted in the casting 209 they thus compensate for the varying thicknesses of the folded part, due to the insertion of the pad, and a substantial pressure will be distributed to the fold during its entire length so as to insure the strip of glue C firmly securing the folds in position.

The slide 201 which carries the folders has pivoted at 211 an adjustable member extending from a cam fork 212. The cam fork 212 carries a cam roller 213 which engages 5 a cam groove in a cam 214 secured to the cam shaft 35. This cam 214 is so set as to cause the slide 201 to be raised and lowered at the proper times.

The shaft 199 to which the short folder 10 197 is secured has fast to it a pinion 215. This pinion meshes a gear segment 216 pivoted on a stud 217 mounted in slide 201. Pivoted at 218 to a tail 219 on segment 216 is a connection 220 secured to or forming part 15 of a cam fork 221. The cam fork 221 carries a cam roller 222, which engages a cam groove in a cam 223 secured to cam shaft 28. This cam is so timed as to cause the short folder to operate when the slide 201 is 20 in its upper position.

The operating parts for the third folder 198 are similar to those described in connection with the short folder 197. A pinion 224 is secured to shaft 200 and meshes a 25 segment 225 also pivoted on stud 217 and having a tail 226. Pivoted at 227 on the tail 226 is a connection 228 forming part of a cam fork 229. The cam fork 229 carries a cam roller 230, which engages a cam groove 30 in a cam 231 secured to the cam shaft 28. The cam 231 is so timed as to cause the third folder to function at the proper time.

From the foregoing the operation of the mechanism for forming the second and third 35 folds will be clear. The means for inserting the sheets of regenerated cellulose or other light, substantially impervious material will now be described. This mechanism is illustrated in Figs. 3 and 34 to 37 inclusive.

40 As previously stated, the sheet of regenerated cellulose is inserted in the sachet while in position *d* of Fig. 3. Fig. 74 shows the sheet of regenerated cellulose *H* in position, where it is held by the strip of glue *D*.

45 A bracket having arms 232 is secured to one of the side frame members 1. Each of the arms 232 carries a pair of rollers 233, which act as bearings for a shaft 234, which carries a reel or spool 235 having a web or roll 236 of 50 regenerated cellulose secured thereto.

As shown particularly in Fig. 35, the sheet of regenerated cellulose passes from the reel 235 under a roller 237 and into the bite of a pair of rollers 238 and 239. The roller 238, 55 which is driven by means hereinafter described, is of substantially large diameter and is mounted in bearings formed in brackets 240 secured to the upper side of one of the side frame members 1.

The roller 239 is carried by arms 241, which are pivoted at 242 in ears extending upwards from the brackets 240. Strong springs 243 secured to pins on the arms 241 and other pins secured to the brackets 240 cause the roller 60 239 to frictionally engage roller 238 so that

when roller 238 is driven the sheet of regenerated cellulose will be advanced.

Means are provided for separating the rollers 238 and 239 so that the regenerated cellulose will not be fed. The reasons for 70 providing a means to stop the feed of the regenerated cellulose are the same as those explained in connection with the raising of the stack of pads *G* so they will not be fed. A hand lever 244 is pivoted on the shaft, which 75 carries roller 239. The lower end of this hand lever 244 carries a roller 245, which will engage the fixed cam 246 when the hand lever is manipulated. This will separate the rollers and the regenerated cellulose will not 80 be fed. Numerous other ways might be devised for stopping the feed of the regenerated cellulose, for instance, a clutch might be provided in the shaft 39, which drives the regenerated cellulose feed roller. This clutch 85 might also be connected to the mechanism for raising the stack of pads so as to simultaneously stop the feed of the pads and of the regenerated cellulose.

A strap 247 may be secured to pivot shaft 90 242 so as to lie over the roll of regenerated cellulose. A weight 248 on the end of the strap will cause the strap to bear against the roll and prevent too much regenerated cellulose from unwinding. 95

The roller 237 keeps the sheet of regenerated cellulose taut between the roll 236 and the rollers 238, 239. This roller is carried by arms 249 pivoted at 250 on the outer ends of the supporting arms 232. As the sheet of regenerated cellulose is being advanced the roller 237 will be raised. After the desired amount has been advanced, the roller 237 will drop and its weight will unwind a sufficient amount of regenerated cellulose to be fed on the next operation. A spring buffer 251 may be provided to prevent the roller 237 dropping too abruptly and unwinding an unnecessary amount of regenerated cellulose from the roll. 105

110 After the regenerated cellulose leaves the feeding rollers 238, 239, it passes between two plates 252 and 253. These plates are shown in cross section in Fig. 36 and it will be noted that the opening or aperture between them is curved. It is well known that regenerated cellulose is an extremely light and delicate material to handle. As the regenerated cellulose is projected from this opening, the latitudinal curve gives it sufficient rigidity so that it will pass onto the sachet without sagging. The curved plates 252 and 253 also prevent any buckling or curling of the regenerated cellulose after leaving the rollers 238, 239. 115

The lower plate 252 is fixed in the brackets 240 and the upper plate 253 is secured to a cross-bar 254 which is removably mounted in pockets 255 formed in the brackets 240. This plate may be removed so as to make it 120 125

easier to thread the regenerated cellulose through the feeding mechanism when a new roll is substituted on the reel 235.

The cross-bar 254 is preferably made of hardened steel and acts as the fixed member 5 of a pair of shears for cutting the regenerated cellulose. The movable member of the shears is designated 256 and is pivoted at 257 on one of the brackets 240. A shield 258 is secured to the cross-bar 254 to prevent anything coming in contact with the shears.

The means for rotating the regenerated cellulose feed roller 238 will now be described. Secured to the shaft of the regenerated cellulose feed roller 238 is a ratchet wheel 259. A pawl 260 is pivoted on a carrier 261, which is freely mounted on the shaft of roller 238. Pivoted at 262 to the carrier 261 is the upper end of a cam fork 263. This cam fork 263 carries a cam roller 264, which engages a cam groove in the cam 265 secured to the shaft 39. In the position of the machine shown in Fig. 34, the pawl 260 is being moved counterclockwise by the cam 265. When it passes 25 a tooth, it will slip behind it and the cam 265 will then cause the pawl to move in a clockwise direction about a third of a revolution, which is sufficient to advance a sheet of regenerated cellulose of the required size.

Immediately upon the necessary amount of regenerated cellulose being advanced it is cut off by the shears heretofore described. The mechanism for operating the shears will now be described. As previously mentioned, 35 the movable member 256 of the shears is pivoted at 257. This pivot 257 is in the form of a stud, which is freely mounted in bracket 240 and has a spring 266 surrounding it. The spring 266 bears against a nut on the end 40 of the stud and the bracket 240 and insures positive engagement of the two cooperating parts of the shears. The shear member 256 has an ear 267, to which is pivoted at 268 an adjustable part of a cam fork 269. The cam 45 fork 269 carries a cam roller 270, which engages a cam groove in a cam 271 secured to the cam shaft 39. This cam 271 is so set as to operate the shears when the required amount of regenerated cellulose has been advanced.

While the sheet is in position *d*, ironing or pressing means are provided to press the air from between the first fold and from between the sheet of regenerated cellulose and the body portion 48 of the main sheet. This 55 pressing means also insures the strips of glue E and F holding the first fold in position and the strip of glue D holding the sheet of regenerated cellulose in position. In conjunction with this pressing means, means are provided for holding the sheet of regenerated cellulose in position while the shears are cutting it and preparatory to the main pressure foot coming in contact with the sheet.

60 The pressing means is shown generally in

Figs. 1 and 3, and in detail in Figs. 29, 31, 32, 33 and 34.

The presser foot comprises a member 272, which is mounted for vertical movement. The member 272 has secured to its lower part 70 a fixed plate 273, which covers a substantial part of the body portion 48 of the sheet. A movable plate 274 is secured to an extension 275 from the member 272. This movable plate 274 presses on that area of the sheet 75 where the turned-over part of the first fold is made and insures a sharp crease being formed.

The movable plate is carried on studs 276 which are freely mounted in the extension 275 and yielding held away from the extension by springs 277. In its normal position, as indicated in Figs. 32 and 33, the forward part of the plate is spaced further away from its mounting than the rear part and that part furthest from the crease is further away from the extension 275 than the part over the crease. This results in the forward part of the plate and that part nearest the crease contacting with the sheet first. With this construction the air between the folds will be forced out more efficiently and a greater pressure will be applied to the sheet in the region of the crease so as to insure a sharp and permanent crease.

90 The means for holding the regenerated cellulose while it is being cut will now be described. Mounted in the member 272 is a plunger 278, which is pressed downward by spring 279 (see Fig. 31). The plunger has a fin 280, which moves in a slot 281 in the member 272 and plate 273 to prevent it from turning. The regenerated cellulose will strike the fin 280 and be gently led to its proper position. Immediately upon its being properly positioned, the end of the plunger 278 will hold it there until the sheet has been cut and the presser foot proper engages the sheet.

100 The means for moving the pressing device up and down will now be described. Pivoted at 282 on a lug secured to member 272 is a lever 283, which is pivoted at 284 on a bracket 285 bolted to one of the side frame members 1. The other end of lever 283 is pivoted at 286 to an adjustable extension from a cam fork 287. The cam fork 287 carries a cam roller 288, which engages a cam groove in a cam 289 secured to the cam shaft 28. The cam 289 is so cut as to raise and lower the pressing means at the right time. A link 290, pivoted at 291 to another lug on the member 272 and at 292 to the bracket 285, keeps the member 272 in proper position when it is being raised and lowered.

110 The sachet is now moved by one of the grippers to position *e* of Fig. 3. In this position the fourth, fifth and sixth folds are made, the glue is applied for holding these 120

130

10 folds together and the sachet is practically completed.

Fig. 75 shows the sachet with the fourth fold made. Fig. 76 shows at K the three spots of glue applied to the under side of the sachet and used for holding the last fold of the sachet in position. In this same view the one spot of glue for securing the fifth fold is indicated at L. Fig. 77 shows the fifth fold completed, and Figs. 78 and 79 show the sixth or last fold made and the sachet completed.

15 The mechanism for making the fourth and sixth folds will first be described. This mechanism is indicated generally in Figs. 1 and 3 and shown in detail in Figs. 38 to 42, and Figs. 44 to 50 inclusive. Figs. 45 to 49 inclusive illustrate the operation and show the various positions of the parts in making 20 these two folds.

25 Means are provided for scoring the sachet along the lines of the folds preparatory to making the folds, and means for holding the sachet in position at times during the folding operations and also for pressing the sachet after the folds have been completed.

30 An overhanging supporting bracket 293 is bolted or otherwise secured to one of the side frame members 1. This bracket has a guideway 294, in which a slide 295 is mounted for vertical movement. The slide 295 has secured to it a pair of blades 296 and 297, which act as scorers. Mounted in the slide is a pair of headed pins 298, which are yieldingly held 35 away from the slide by springs 299. These pins are mounted in the slide between the scorers 296 and 297, and as hereinafter will be apparent they act to hold the sachet in position while the fourth fold is being made.

40 The slide 295 also carries two presser feet 300, which are supported on studs or pins 301 yieldingly held away from the slide by springs 302. As will appear later in this description the presser feet 300 function to 45 hold the sachet in position at times during the folding operation.

45 The bracket 293 has another guideway 303 formed therein, and in this guideway is mounted for vertical movement a second slide 50 304. This slide 304 carries a pair of pressing fingers 305, which act, as will later be apparent, to exert a substantial pressure on the sachet after the last fold has been made.

An auxiliary slide 306 is carried by the 55 slide 304. This slide has a depending foot 307, which acts on the sachet just prior to the pressing fingers 305.

60 The mechanism for reciprocating the slides 295 and 304, which is particularly illustrated in Fig. 38, will now be described. A roller 308 is mounted in a pair of ears 309 secured to slide 295. This roller is engaged by the bifurcated end of a lever 310, which is pivoted at 311 to an ear on the bracket 293. The other end of the lever 310

is pivoted at 312 to an adjustable extension from a cam fork 313. A cam roller 314 secured to the cam fork 313 engages a cam groove in a cam 315, which is fastened to the cam shaft 28. This cam 315 is so timed as 70 to raise and lower the slide 295 at the proper times.

The bifurcated end of a lever 316 engages a pin 317 secured to the slide 304. This lever 15 75 316 is pivoted at 318 on the bracket 293 and its other end is pivoted at 319 to an adjustable extension from a cam fork 320. The cam fork 320 carries a cam roller 321, which engages a cam groove in a cam 322 secured to the cam shaft 28 adjacent cam 315. The cam 80 322 will cause the slide 304 to be raised and lowered so as to properly function.

When the sheet or sachet is being moved 85 from one position to another by the grippers 25, the mechanism for making the fourth and sixth folds lies below the table 4, as does the mechanism for making the second and third folds. When the sheet or partially completed sachet comes to rest at position e, this mechanism is raised and then functions. 90

A bracket 323, suitably secured to one of the side frame members 1, has a guideway 324 in which a slide 325 is mounted for vertical movement. An arm 326 is secured to the bracket 323. This arm supports a pair of studs 327 which carry a platform 328 on their upper ends. The studs have upper and lower collars 329 on either side of the supporting arm 326. When the upper collars 329 are resting on the supporting arm 326, the platform 328 is flush with the table 4 and acts as a continuation of the table for supporting the sheets or partially completed sachets as they are moving onto it to position e or away 100 from it to the succeeding position. During the operation of the folding mechanism the table or platform 328 is slightly raised, so that the lower collars 329 abut the supporting arm 326 and limit the upward movement. 105

Pivoted at 330 in the bracket 323 is a short 110 link 331. Screwed or otherwise secured to the upper side of this link is one leg of an angled plate 332. Fastened to the other leg of the plate 332 by a screw and slot connection 333 is the folder 334. The screw and slot 115 connection 333 permit of adjustment of the position of the folder 334. Tongues 335 on the table 4 extend between the fingers of the folder, so as to provide additional support for the sheet or partially finished sachet. 120

Pivoted on the outer end of the link 331, at 336, is another short link 337, to which is pivoted a cam fork 337. The cam fork 337 carries a cam roller 338, which engages a groove in a cam 339 secured to the cam shaft 125 35. The cam 339 causes the folder 334 to function at the proper time.

Mounted in an extension 340 of the slide 325 is a pinion 341, which is engaged by teeth 342 of a reciprocable rack bar 343. The stud 130

344, to which the pinion 341 is secured, carries an arm 345, see Fig. 51. Freely mounted on a continuation of this stud 344 is an oscillating platform 346. The end of stud 344 is 5 journaled in an ear on platform 346. An ear on the opposite side of the platform has a free journal 347 in an upward extension of the slide 325. A flat spring member 348 may be drawn up against this ear so as to frictionally engage it and cause the platform to 10 maintain its proper relation to parts herein-after described.

The arm 345 has pivoted on its outer end at 349 a link 350. This link in turn is pivoted 15 at 351 to another link 352, which is pivoted at 353 to ears on the table 346. The link 352 has a pair of toes 354 having sloping ends. Secured to the link 352 is a pair of gripping fingers 355, which hold the fourth fold in 20 place after it has been positioned by the folder 334.

Mounted on extensions 356 of the slide 325 or formed integral with it is a table 357. This table has clearance holes for the studs 25 327 and by virtue of these clearance holes the table 328 will only be raised slightly at the end of the upward movement of the slide 325.

Particular attention is now directed to 30 Figs. 45 to 49, which illustrate in detail the operation of the mechanism of the fourth and sixth folds. It will be understood that the fifth fold is being made by other mechanism hereinafter described before the sixth or last 35 fold is completed. The fourth fold takes care of the short end of the second and third folds extending beyond the pad G and is shown completed in Fig. 75.

In Fig. 45 the partially completed sachet, 40 which is indicated in broken lines, is just approaching position e of Fig. 3. The folder 334 is withdrawn and the slide 335 and all its associated parts are in their lower position, the platform 328 being flush with the table 4. The scorers 296 and 297, pins 298 and presser 45 feet 300 are descending and are part way down.

Fig. 46 shows the partially completed sachet as having reached position e. The slide 50 325 has almost reached the end of its upward movement. The scorers 296 and 297 have scored the partially completed sachet on either side of the pad G where the folds are to be made, and they are moving away from 55 the sachet. The fourth fold has been given an initial start by the scorer 296 and the raised sloped edge 358 of the table 346. The folder 334 is still in its withdrawn position and the gripping fingers 355 have not moved 60 from the position of Fig. 45. The headed pins 298 are pressing on the sachet and firmly holding it in position.

In Fig. 47 the slide 325 has reached the end of its upward movement and the platform 65 328 is slightly elevated above the table

4. The folder 334 has functioned and the fourth fold is almost complete. The arm 345 has been rotated a sufficient amount by its pinion 341 to cause the grippers 355 to engage the fourth fold. The presser feet 300 and headed pins 298 are bearing on the partially completed sachet and are almost ready to leave it. A slight further advance beyond the position of Fig. 47 and the grippers 355 will be firmly holding the sachet against the 70 table 346.

After the grippers 355 have reached their final position and the links 350 and 352 are approximately at right angles to each other, a continued rotation of the arm 345 causes 80 the table 346 to rotate on its pivots 345 and 347. The parts will then assume the position indicated in Fig. 48.

The grippers 355 are still holding the sachet 85 against the table 346 and the table 346 has been moved about 90°, thus completing about half of the sixth or last fold. The pins 298 and presser feet 300 have been withdrawn. At this time the other portion of the sachet is being firmly held by the mechanism completing the fifth fold, which will be described hereinafter. In Fig. 48 the folder 90 334 has been withdrawn.

Reference will next be had to Fig. 49 in 95 which the sixth or last fold has been completed, it being understood as previously stated that the fifth fold will be finished before this position is reached. The arm 345 moves the table 346 almost to the position of Fig. 49. Just prior to the parts reaching the position of Fig. 49, the foot 307 on the auxiliary slide 306 hits the sachet a sharp blow and helps to complete the last fold. The foot 307 passes through a notch or opening 359 left in the table 346. The auxiliary slide 100 306 being freely mounted in the slide 304 moves upward and the fingers 305 on this slide bear against the table 346 and exert a substantial pressure on it so as to insure the glue adhering to the folded parts.

As stated, the arm 345 moves the table 346 almost to the position of Fig. 49. The fingers 305 complete the movement, and before they are raised from the table 346 the arm 345 starts to move in the opposite direction. This causes the linkage 350, 352 to withdraw 105 the grippers 355. When they are completely withdrawn, the sloping ends of the toes 354 on the link 352 rest against the under side of the table 346. The pressing fingers 305 are withdrawn and a continued movement of arm 345 returns the table to its normal position and the slide 325 retracts the folding mechanism to the position of Fig. 45.

From the foregoing it is thought that the 115 operation of the fourth and sixth folds should be clear. The means for reciprocating the slide 325 and rotating the arm 345 will now be described.

Pivoted at 360 on a lug of the slide 120 130

is an extension from a cam fork 361. This cam fork 361 carries a cam roller 362, which engages a cam groove in a cam 363 (see Fig. 42) secured to the cam shaft 28. Pivoted on the stud on which cam roller 362 is mounted is an arm 364, as shown in Fig. 41. One end of this arm carries a cam roller 365, which engages a cam groove in a cam 366 secured to cam shaft 35 adjacent the cam 363. The 10 other end of the arm 364 is pivoted at 367 to the rack bar 343. The cams 363 and 366 are so designed as to cause the slide 325 to raise and lower at the proper time and to cause the arm 345 to operate in proper relation to the 15 raising and lowering of slide 325.

The means for applying the three spots or drops of glue K for securing the last fold in position will now be described. Pivoted at 367 on a stud 368 extending from the lever 20 310 is a depending arm 369 (see Fig. 43). This depending arm 369 has a notch 370, which engages a toe 371 on a weighted lever 372.

The lever 372 is secured to a rod 373, which 25 has bearings in the sides of a glue container 374. The rod 373 has a plurality of fingers 375, three in this instance, secured to it. These fingers 375 normally lie in the glue contained in the vessel 374. A spring 376 30 extending between the lever 310 and the depending arm 369 maintains the arm 369 in contact with the lever 372.

The lever 310 moves up and down to operate the slide 295. On its downward movement the notch 370 in the depending arm 369 will engage the toe 371 on the lever 372 and cause the fingers 375 to be raised. They will pass through openings 377 in the table 4 (see Fig. 38) and carry the three drops of glue K 40 to the under side of the body portion 48 of the sheet A as shown in Fig. 76. The notch 370 will trip past the toe of the lever 372 and the weight of the lever and the fingers 375 will cause the fingers to again be immersed in 45 the glue.

If desired, more than three fingers could be used or under other conditions the flap 44 of the first fold might be very narrow and only one drop of glue would be applied there- 50 to.

A slotted guide plate 378 is preferably secured to the table 4 to insure the depending arm 369 maintaining its proper relation to the lever 372. The depending arm 369 may 55 be withdrawn from the guide plate 378 and swung around on the stud 368 and slipped into a notched plate 379 on the lever 310. It is desirable to do this when removing the glue container 374 to replenish the supply of glue. 60 The glue container 374 is supported on a plate 380 carried on one of the side frames 1, and suitable means are provided for holding it in position. As illustrated, this means comprises a ledge on the plate 380 and a cham- 65 fered stud 381.

The means for applying the drop of glue L is particularly illustrated in Figs. 44 and 60 and will now be described. A bracket 382 is bolted or otherwise secured to one of the side frames 1. This bracket 382 has a pair of ears 383 which act as guides for a plunger 384. The plunger will drop by gravity and is raised by the bifurcated end of a lever 385 contacting with a stop collar 386 on the plunger. The downward movement of the plunger 70 is limited by a collar 387 on its upper part contacting with the upper one of the ears 383.

The lower part of the plunger 384 is reduced at 388 and is provided with a shoulder 389 which will act to prevent the glue working up into the bearings for the plunger. The reduced end 388 passes through an opening 390 in the platform 4 and enters an opening 391 in a glue reservoir 392 which is supported on a plate secured to one of the side 80 frames 1. The glue reservoir 392 is provided with a cylindrical chamber 393, so as to hold a larger volume of glue. The chamber 393 has a filling cap 394.

A buffer spring 395 is coiled about the 90 plunger 384 above the collar 386. As the plunger is rapidly raised by the lever 385, this spring 395 will contact with the upper one of the ears 383 to prevent wear and make for noiseless operation.

In the operation the end 388 of the plunger dips into the glue reservoir, just prior to the sheet reaching the position e and is then raised. Immediately upon the sheet reaching the position e it drops again and deposits 100 the drop of glue L, after which it is instantly raised.

The lever 385 is pivoted at 396 to the bracket 382 and its outer end is pivoted at 397 to an adjustable extension from a cam fork 398. The cam fork 398 carries a cam roller 399, which engages a cam groove in a cam 400 secured to the cam shaft 28. This cam is so laid out as to cause the plunger 384 at the proper times to make the two rapid up and 105 down movements, one into the glue reservoir and the other to deposit the drop of glue.

The mechanism for making the fifth fold will now be described. This mechanism is generally indicated in Figs. 1 and 3 and illustrated in detail in Figs. 52 to 59 inclusive. Figs. 55 to 59 are schematic views showing different consecutive positions of the parts 115 while the fifth fold is being made.

The scorer for this fold will first be described. A blade 401 is secured on a slide rod 402. The slide rod 402 is reciprocated in ears on a bracket 403 secured to one of the side frame members 1. The slide rod and scorer blade move in angular relation to the 120 table 4 and at the operating end of its stroke the edge of the blade 401 contacts with the partially completed sachet to score it or crease it at the proper place for the fold.

Pivoted at 404 on the slide rod is a link 405. 125

This link 405 is pivoted at 406 to another link 407, which in turn is pivoted at 408 to a bracket 409 bolted or otherwise secured to one of the lower side frame members 2. The link 407 is guided between a pair of angle members 410 secured to one of the upper side frame members 1.

Pivoted at 411 on the intermediate part of the link 407 is a cam fork 412. This cam fork 412 carries a cam roller 413, which engages a cam groove in a cam 414 secured to the cam shaft 35. The cam 414 is so timed as to cause the scorer 401 to function at the proper time.

The blades for making the fold and their operating parts will now be described. A pair of slides 415 and 416 are mounted for horizontal reciprocation in angle guides 417 secured to a side frame member 1 on the side opposite the scorer. The upper of these slides 415 is the folding slide and the lower cooperates with the scorer and then acts as a holding slide.

The upper slide 415 is secured to or made integral with a bar 418. A pair of lateral ears 419 are formed on this slide. Behind the ears 419 is a depending projection 420 having an inclined face 421. Pivoted at 422 on the outer end of the bar 418 is a lever 423. The other end of this lever is pivoted at 424 to a bracket secured to one of the lower side frames 2. A cam fork 425 is pivoted at 426 to the lever 423. The cam fork 425 carries a cam roller 427, which engages a cam groove in a cam 428 secured to the cam shaft 28. This cam reciprocates the slide 415 at the proper time to perform its desired functions.

The lower slide 416 is secured to or formed integral with a bar 429. The bar 429 has a pair of fingers 430, which cooperate at times during the operation with the ears 419 on bar 418, for reasons hereinafter explained. The bar 429 is provided with a depressed portion 431 and a notch 432 having a sloping face 433. The outer end of the bar 429 has a set-screw 434 threaded into it. This set-screw may be adjusted, and its head contacting with the angle guide members 417 acts as a limit stop for the inward movement of slide 416.

A slide 435 is pivoted at 436 to the bar 429. This slide is normally pulled downwards by a spring 437, one end of which is attached to the slide and the other end to a cam fork 438. The cam fork 438 has a guideway, which has pin and slot connections 439 with the slide rod 435.

Pivoted at 440 on the slide 435 is a rod 441, which passes through a clearance hole in the flange of one of the side frame members 1. This rod is surrounded by a spring 442 which normally urges the slide rod 435 and slide 416 toward the center of the machine.

The cam fork 438 carries a cam roller 443, which engages a cam groove in a cam 444 secured to the cam shaft 35. This cam 444 is so cut as to cause the slide rod 435

to slightly elevate the slide 416 for purposes hereinafter described.

Particular reference will now be had to Figs. 55 to 59 inclusive, which illustrate the operation. In Fig. 55 the parts are in approximately the same position as in Fig. 45. The partially completed sachet has arrived at about its position *e* of Fig. 3. The parts that have been explained in detail in the description of Figs. 45 to 49 will not be dwelt on to any extent in this description and have not been illustrated in Figs. 55 to 59 except such parts as have direct bearing on the mechanism for this fold.

In Fig. 55 the slides 415 and 416 and their associated parts have not started to function. The presser feet 300 are advancing toward the platform 328, and the second platform 357 on slide 325 has not been raised.

In Fig. 56 the platform 328 has been raised by the table 357 and the scorer blade 401 has been projected to its operating position. The presser feet 300 have been brought down to hold the sachet in position, and the slides 415 and 416 are about to function.

In Fig. 57 the scorer 401 is still in its operative position and the presser feet 300 still holding the sheet or partially finished sachet. In this figure the lower slide 416 and its bar 429 have been projected forward by the spring 442. In the position of Figs. 55 and 56, the fingers 430 on bar 429 contacting with the ears 419 on the bar 418 prevent the bars from moving away from each other, and the depending projection 420 engaging the notch 432 prevents the bar 429 and slide 416 from being projected toward the table 328.

In Fig. 57 the slide 415 and its bar 418 have been projected forward and the ears 419 have moved away from the fingers 430, thus permitting the spring 442 to force the bar 429 and scorer 416 forward its maximum amount. The set-screw 434 will act as a stop for any further horizontal movement of the bar 429 and slide 416.

During this forward movement of slide 416 the slide rod 435 has been raised by the cam 444 so as to elevate the slide over the scorer blade 401 and cause a sharp crease to be made for the fold.

In the position of Fig. 57 the sloping face 421 of the depending portion 420 of slide 416 has ridden up on the sloping face 432 of the notch 433 in the bar 429 and caused the folding slide 415 to gently raise the part of the sachet to be folded. This is indicated in broken lines in Fig. 57.

In Fig. 58 the scorer 401 has been withdrawn. Immediately upon the withdrawal of the scorer the spring 437 pulls the holding slide 416 against the edge of the table 357 and firmly grips the folded edge. This adds further to making a sharp fold and also holds the sachet while the fifth and sixth

10 folds are being completed as the presser feet 300 have now been withdrawn.

In Fig. 58 the depending portion 420 is entering the depressed portion 431 of the bar 429. This will cause the slide 415 to travel closer to the table 328 and insure a neater fold. It also permits of the folder 415 applying sufficient pressure to cause the drop of glue L to adhere to the cellophane. In 10 Fig. 58 the parts are in substantially the same position as they are in Fig. 48.

In Fig. 59 the fifth and sixth folds have been completed and the slide 415 and its bar 418 are being withdrawn. Just prior to the 15 ears 419 engaging the fingers 430 so as to withdraw the holding slide 416, the cam 444, through the medium of the slide rod 435, slightly raises the slide 416 so that the holding slide may be easily released from its holding 20 position, and there will be no possibility of the sheet being injured.

The ears 419 will contact with the fingers 430 and the depending portion 420 will engage the notch 432 and the parts carried back 25 to the position of Fig. 55, where they will be ready for the next cycle of operation.

It is thought from the foregoing that the 30 operation of the mechanism for the fourth, fifth and sixth folds will be clear. The mechanism illustrated and described is a preferred embodiment and has proven exceedingly successful in operation, but other suitable constructions might be substituted for performing the desired operations.

35 The completed sachet is now carried by one of the grippers to position f. In this position it is given a final pressing, means are provided for opening the gripper, and means for carrying the completed sachet from the machine.

40 The means for giving the completed sachet its final pressing and opening the gripper 25 will first be described. This is shown in a general way in Figs. 1 and 4 and illustrated more in detail in Figs. 65 and 66.

45 A presser foot 445 is secured by screw and slot connections 446 to the end of a lever 447, the screw and slot connections 446 permitting of vertical adjustment of the presser foot. The presser foot has a thickened portion 448 which engages the flat part of the sachet and the thinner portion of the presser foot engages the part of the sachet in which the pad G is wrapped.

50 Secured to the side of the lever 447 opposite to where the presser foot is held is an extending arm 449. When the lever 447 is depressed and the presser foot engages the sachet, the arm 449 will engage the gripper holding the sachet and open it, and the gripper will be held open while in contact with this arm 449.

55 The lever 447 is pivoted at 450 on a bracket secured to one of the side frames 1. The other end of the lever 447 is pivoted at 451 to an adjustable extension of a cam fork 452. The cam fork 452 carries a cam roller, which

engages a cam groove in a cam 453 secured to the cam shaft 28.

Immediately upon the sachet reaching the position f the cam 453 through the medium of cam fork 452 will raise the outer end of the lever 447, thus depressing the inner end and causing the extending arm 449 to contact with the gripper 25 so as to release the sachet. The presser-foot will also function at this time. The gripper is held open by the arm 449 until it has traveled well beyond the completed sachet. A traveling belt, hereinafter described, will then carry the completed sachet from the machine.

If there should be any tendency for the 80 sachets to stick to the presser foot 445, simple means are provided for preventing this. Secured in an arm 454 fixed to the table 4 is a rod 455. The lower end of this rod has an enlargement 456, which passes through an 85 opening 457 in the presser foot. If the sachets should adhere to the presser foot, they will come in contact with the enlargement 456 as the presser foot rises and will be forced to drop off the presser foot.

90 The means for carrying the completed sachet from the machine will now be described. This means is illustrated in Figs. 4, 38, 65 and 66.

95 When the sachet comes to rest in position f, it is located on a belt 458 which runs over rollers 459 and 460. The roller 459, which is an idle roller, is journaled about the center of the machine adjacent the sprocket chain 20, and the roller 460, which is of larger diameter 100 and is the driven roller, is journaled on the ends of brackets 461 secured to one of the side frame members 1.

105 The brackets 461 also support tables 462, which cover some of the working parts of the machine and allow ample space for the operator to stack up the finished sachets. In Fig. 4 parts of these tables are broken away for clearness of illustration and economy of 110 space.

115 The belt 458 is moved intermittently. It is at rest while the sachet is being pressed and the gripper 25 is opened, and starts its movement just prior to the gripper closing. It is moved a distance of about the width of a sachet, so that a number of sachets may travel side by side on the belt. This gives the operator ample time to count and stack a number of the sachets before she picks the 120 next batch of finished ones from the belt.

125 The roller 460 has a shaft 463. Secured to the shaft 463 is a two-toothed ratchet wheel 464. Adjacent the ratchet wheel 464 and freely mounted on the shaft is a gear 465. Integral with or secured to the gear is a flange 466 which carries a spring-pressed pawl 467.

130 A rack 468 secured to a connecting rod 469 engages the gear 465. As the rack is moved outward the pawl will be brought in contact

with one of the teeth on the ratchet 464. When the rack is moved in the opposite direction the pawl will rotate the ratchet wheel a half a revolution and the belt 458 will be advanced a sufficient distance.

The other end of the connecting rod 469 is secured to a cam fork 470 (see Fig. 65) which carries a cam roller 471. The cam roller 471 engages a cam groove in a cam 472 secured to 10 the cam shaft 35. The cam 472 is so laid out as to operate the driven roller 460 at the proper time.

A belt-tightening roller 473 is carried on an arm 474 pivoted at 475 to an ear on the 15 bracket 461.

The grippers 25 for carrying the sheets or partially completed sachets from one station to another might be of any desired construction. However, a preferred form of these 20 grippers is illustrated in Figs. 61 to 64 and will now be described.

The fixed jaw of the gripper which is secured to the chain 20 comprises an angle member having two legs 476 and 477. The 25 leg 476 is secured to one of the links of the sprocket chain 20 and projects upward through the slot 24 in the table 4.

The other leg 477 is somewhat thinner and 30 lays slightly above the table 4 as it is traversing the length of the machine. The forward edge of this leg is rounded off at 478 so as to eliminate any possible interference with the sheet as the operator is inserting the same between the jaws.

35 The rear part of the leg 477 is provided with a pair of ears 479, in which is mounted a pintle 480. This pintle has the movable jaw 481 secured to it between the ears 479 by a set-screw 482.

40 One end of the pintle 480 extends beyond one of the ears 479 and has a coiled spring 483 round about it. One end of the coiled spring 483 is secured to a pin 484 projecting from the pintle 480 and the other end is secured to a part 485 struck up from the leg 477. This spring will maintain the jaws of the 45 gripper in their closed position.

The movable jaw 481 has a tail 486, which is depressed so as to open the gripper when 50 the sheet is being inserted at the feeding end of the machine, as heretofore described, and again to open the gripper so that the completed sachet may be carried away from the machine.

55 It is essential for the successful operation of the machine that the gripper firmly hold the sheet at all times so as to eliminate any possibility of the sheet canting. The jaw proper 487 is mounted in a mouth 488 in the member 481. Two small pins 489 extend across the mouth 488 and pass through clearance holes in the jaw proper 487. The member 487 preferably only has its ends 490, as shown in Fig. 62, contact with the plate 477. 60 65 By virtue of the pins 489 passing through

slightly enlarged holes and the clearance in the mouth 488, the jaw member 487 is bound to positively seat itself and hold the sheet firmly at all times.

Means are provided for turning the machine over by hand so that when it is necessary the operator may bring the machine to any desired position for making minor adjustments or when removing the glue containers for cleaning and replenishing or when 70 75 inserting a new supply of cellophane.

The hand-operating mechanism is illustrated in Figs. 1 and 7. A shaft 491 is mounted in bearings 492 secured to the frame members 2. One end of this shaft is provided with a hand wheel 493 and the other end with a bevel gear 494. The bevel gear 494 meshes a bevel gear 495 secured on a longitudinally extending shaft 496. The other end of shaft 496 is suitably clutched to the 80 85 driving pulley 18.

In the illustrated embodiment of the invention the machine is intermittently operated in the sense that the motion of the material through the machine is intermittent. However, it is considered quite advantageous to have some of the functions performed while the machine is in motion, for instance the applying of the strips of glue. In a number of the stations parts of the operation are also performed while the material is in motion. In accordance with the invention, a number of operating stations are working simultaneously on a sachet or partially completed sachet and a certain 90 95 operation is completed at each station so that upon the emergence of the sachet from the last station a finished article is produced after having been operated upon by a multiplicity of mechanical movements. This arrangement makes for an extremely smooth running machine and greatly increased production of the machine.

It is considered important and special attention has been directed to wrapping and sealing the non-porous sheet of material snugly or tightly about the pad and depending upon the adhesiveness of the glue to hold it there. This will be particularly evident 100 105 from an inspection of the mechanism forming the second, third and fourth folds.

Importance is also attached to the method of loosely folding that part of the non-porous or main sheet extending beyond the wrapped object about the inserted sheet of impervious material. The impervious material is secured or tacked to the wrapper or non-porous sheet in such a manner as to permit of easy winding and more ready manipulation of the completed sachet about the tress of hair. Other means of securing the sheet of impervious material to the wrapper or main sheet might be utilized without sacrificing 115 120 125 this result.

As illustrated and described the three spots 130

or drops of glue K maintain the sixth or last fold in position. Other means such as stapling or sewing might be utilized for this purpose.

5 The operation of the machine having been gone into thoroughly as the sheet or partially finished sachet reached the various different positions in the machine, it is thought to be clear and not essential to elaborate thereon further.

10 Attention is again called to the fact that while the mechanism illustrated and described is for the wrapping and folding of what are termed "sachets," it could readily be used in other fields with slight modifications.

15 The term "regenerated cellulose" is meant to cover any light, substantially impervious material, or in wrapping other packages than the sachets described it might 20 be a sheet or strip of any suitable material or fabric. Likewise as heretofore suggested any suitable object might be substituted for the pads and wrapped in accordance with the mechanism disclosed.

25 As heretofore stated, many changes might be made in the organization of the machine and the arrangements of parts and mechanisms without departing from the spirit of the invention as set forth in the appended 30 claims.

What is claimed as new is:

1. A machine of the character described, having in combination, means for wrapping part of a sheet of material about an object, 35 means for supplying another sheet of material to the part of said first-mentioned sheet extending beyond the wrapped object, and means for folding part of said first-mentioned sheet about said second sheet.

40 2. A machine of the character described, having in combination, means for wrapping part of a sheet of material about an object, means for folding part of said sheet extending beyond the wrapped object, means for 45 supplying another sheet of material to said first-mentioned sheet, and means for folding part of said first-mentioned sheet about said second sheet.

50 3. A machine of the character described, having in combination, means for perforating a sheet of material, means for wrapping part of the sheet of material about an object, means for supplying another sheet of material to the part of said first-mentioned sheet extending beyond the wrapped object, and means for loosely folding part of said first-mentioned sheet about said second sheet.

4. A machine of the character described having in combination, means for perforating a sheet of material, means for applying glue to the sheet of material, means for wrapping part of a sheet of material about an object, means for folding part of said sheet extending beyond the wrapped object, means for supplying another sheet of material, and

means for loosely folding part of said first-mentioned sheet about said second sheet.

5. A machine of the character described having in combination, means for advancing a sheet of material through said machine, 70 stops against which the sheet of material may be positioned when entering the machine, means for moving said stops from the path of the sheet, means for wrapping part of the sheet about an object, means for supplying another sheet of material to the part of said first-mentioned sheet extending beyond the wrapped object, and means for loosely folding part of said first-mentioned sheet about 75 said second sheet.

6. A machine of the character described having in combination, means for advancing a sheet of material through said machine, means for applying a plurality of strips of glue to said sheet as it is passing through said 80 machine, means for wrapping part of the sheet about an object, means for supplying another sheet of material to the part of said first-mentioned sheet extending beyond the wrapped object, and means for loosely folding part of said first-mentioned sheet about 85 said second sheet.

7. A machine of the character described having in combination, means for advancing a sheet of material through said machine, a 90 plurality of segments having their peripheries in staggered relation to each other for applying strips of glue to said sheet as it is passing through the machine, a plurality of glue transferring rollers mounted in a glue 95 container, means for controlling the amount of glue taken up by said rollers, means for rotating said rollers and said segments, and means for folding part of said sheet of material about an object.

8. A machine of the character described having in combination, means for advancing a sheet of material through said machine, a set of pins adapted to form perforations in part of the sheet, means for forcing said pins into said sheet as it is passing through said machine, means for folding part of said sheet of material about an object, means for supplying another sheet of material to the part 100 of said first-mentioned sheet extending beyond the wrapped object, and means for folding part of said first-mentioned sheet about 105 said second sheet.

9. A machine of the character described having in combination, means for advancing a sheet of material through said machine, a set of pins adapted to form perforations in part of the sheet, a slide to which said pins are secured, a stripper plate yieldingly mounted on said slide, means for reciprocating said slide so as to force said pins to enter said sheet as it is passing through said machine, and means for wrapping part of 110 said sheet of material about an object so that 115

the perforated area of said sheet lies adjacent one side of said object.

10. A machine of the character described having in combination, means for advancing a sheet of material through said machine, said means comprising a sprocket chain provided with a plurality of grippers, means for opening one of the grippers for the reception of the sheet of material, stops against which 10 the forward end of the sheet may be positioned when entering the gripper, means for withdrawing said stops from the path of said sheet, and means for wrapping part of said sheet of material about an object.
15. 11. A machine of the character described having in combination, means for advancing a sheet of material through said machine, means for folding a flap in said sheet of material back onto the body portion of said 20 sheet while it is being passed through the machine, and means for wrapping part of said sheet of material about an object.
25. 12. A machine of the character described having in combination, means for advancing a sheet of material through said machine, a swinging plate for folding a flap in said sheet of material back onto the body portion of said sheet while it is being passed through the machine, means for operating said plate, 30 and means for wrapping part of said sheet of material about an object.
35. 13. A machine of the character described having in combination, means for advancing a sheet of material through said machine, a swinging plate for folding a flap in said sheet of material back onto the body portion of said sheet while it is being passed through the machine, means for clamping said flap to said plate prior to its being folded, means 40 for releasing said clamping means after the fold has been completed, means for operating said clamping means and said releasing means, and means for swinging said plate about 180°.
45. 14. A machine of the character described having in combination, means for advancing a sheet of material through said machine, means for perforating a portion of said sheet of material, means for positioning a pad on said sheet of material as it is being passed through the machine, and means for wrapping part of said sheet of material about said pad.
55. 15. A machine of the character described having in combination, means for advancing a sheet of material through said machine, means for perforating a portion of said sheet of material as it is being passed through the machine, means for positioning a pad on said sheet of material as it is being passed through the machine, and means for wrapping part of said sheet of material about said pad so that the perforated area of said sheet lies adjacent one of the sides of said pad.
60. 16. A machine of the character described

having in combination, means for perforating a portion of said sheet of material, means for advancing a sheet of material through said machine, a magazine containing a stack of pads, means for ejecting the lowermost pad in the stack from the magazine, means for grasping said pad after it has been ejected and positioning it on said sheet of material, the perforated area being adjacent said pad, and means for wrapping part of said sheet 75 of material about said pad.

17. A machine of the character described having in combination, means for advancing a sheet of material through said machine, a magazine containing a stack of pads, means for ejecting the lowermost pad in the stack from the magazine, means for grasping said pad after it has been ejected and positioning it on said sheet of material so that a comparatively narrow strip lies adjacent one side 80 of the pad and a wider strip adjacent the other side of said pad, means for folding the narrow strip of material adjacent said pad over the pad, means for folding the wider strip on the opposite side of said pad over 85 the pad and edge of said narrow strip, and means for holding the pad and sheet during the folding operations.

18. A machine of the character described having in combination, means for advancing a sheet of material through said machine, means for perforating a portion of said sheet of material, means for positioning a pad on said sheet of material as it is being passed through the machine, a pair of folders for 100 folding the parts of said sheet of material adjacent said pad about the pad, and means for operating said folders.

19. A machine of the character described having in combination, means for advancing a sheet of material through said machine, means for perforating a portion of said sheet of material, means for positioning a pad on said sheet of material as it is being passed through the machine, a pair of folders for folding the parts of said sheet of material adjacent said pad about the pad, said folders normally resting below the path of travel of said sheet as it passes through the machine, means for raising said folders to approximately the level of the sheet, and means for rotating said folders.

20. A machine of the character described having in combination, means for advancing a sheet of material through said machine, means for perforating a portion of said sheet, a magazine containing a stack of pads, a slide in the lower part of said magazine for projecting the lowermost pad in the stack, means for projecting said slide, grippers to grasp the pad while on said slide, means for withdrawing said slide from beneath said pad, means for moving said gripper to position said pad upon the sheet, means for releasing said grippers from said pad, and means for 120

125

130

wrapping part of said sheet about said pad, the perforated area being adjacent said pad.

21. A machine of the character described having in combination, means for advancing a sheet of material through said machine, means for wrapping part of said sheet of material about an object while passing through said machine, and means for projecting a sheet of substantially impervious material onto said first-mentioned sheet.

22. A machine of the character described having in combination, means for advancing a sheet of material through said machine, means for wrapping part of said sheet of material about an object while passing through said machine, means for supporting a roll of substantially impervious material on said machine, means for feeding the impervious material onto the sheet of material, and means for cutting off the strip of impervious material fed onto said sheet of material.

23. A machine of the character described having in combination, means for advancing a sheet of material through said machine, means for wrapping part of said sheet of material about an object while passing through said machine, means for supporting a roll of substantially impervious material on said machine, means for feeding the impervious material onto the sheet of material, means for cutting off the strip of impervious material fed onto said sheet of material, and means for holding the impervious material while it is being cut.

24. A machine of the character described having in combination, means for advancing a sheet of material through said machine, means for wrapping part of said sheet of material about an object while passing through said machine, means for projecting a strip of regenerated cellulose or similar material onto said sheet of material, curved guide plates through which said strip of regenerated cellulose is projected, and means for cutting said strip of regenerated cellulose.

25. A machine of the character described having in combination, means for advancing a sheet of material through said machine, means for wrapping part of said sheet of material about an object while passing through said machine, means for supporting a roll of substantially impervious material on said machine, means for projecting a sheet of said impervious material onto the wrapper sheet, said means comprising a pair of feeding rollers between which the impervious material passes, means for intermittently rotating said feed rolls, curved guide plates between which the impervious material passes after leaving said feed rolls to prevent buckling or curling of said impervious material, and means at the open end of said curved guide plates for cutting the strip of

impervious material projected onto said sheet of material.

26. A machine of the character described having in combination, means for advancing a sheet of material through said machine, means for folding a flap in said sheet of material back onto the body portion of said sheet of material while it is being passed through the machine, means for projecting a strip of regenerated cellulose or similar material onto the body portion of said sheet of material, means for applying pressure to said turned over flap and said strip of regenerated cellulose and the sheet, and means for wrapping part of said sheet of material about an object.

27. A machine of the character described having in combination, means for advancing a sheet of material through said machine, means for folding a flap in said sheet of material back onto the body portion of said sheet of material while it is being passed through the machine, means for projecting a strip of regenerated cellulose or similar material onto the body portion of said sheet of material, a reciprocable member, a presser foot carried by said reciprocable member, part of said presser foot over the crease between said flap and said body portion being yieldingly mounted, means for moving said reciprocable member up and down so that the presser foot will engage said turned over flap and said strip of regenerated cellulose and the sheet, and means for wrapping part of said sheet of material about an object.

28. A machine of the character described having in combination, means for advancing a sheet of material through said machine, means for positioning a pad on said sheet of material as it is being passed through the machine, means for folding portions of said material adjacent said pad over said pad, a folder for folding the folded portion of said material adjacent and beyond the pad over the pad, and grippers for holding said portion.

29. A machine of the character described having in combination, means for advancing a sheet of material through said machine, means for positioning a pad on said sheet of material as it is being passed through the machine, means for folding portions of said material adjacent said pad over said pad, means for folding the folded portion of said sheet adjacent and beyond the pad over said pad, and reciprocable means for scoring said portion along the line of fold.

30. A machine of the character described having in combination, means for advancing a sheet of material through said machine, means for positioning a pad on said sheet of material as it is being passed through the machine, means for folding portions of said material adjacent said pad over said pad, means for folding the folded portion of said sheet

adjacent and beyond the pad over said pad, means for holding said pad and sheet while being folded, and grippers for holding said last-mentioned folded portion after being 5 folded.

31. A machine of the character described having in combination, means for advancing a sheet of material through said machine, means for positioning a pad on said sheet of 10 material as it is being passed through the machine, means for folding portions of said material adjacent said pad over said pad, means for folding the folded portion of said material adjacent and beyond the pad over 15 said pad, and means whereby said pad is laid over so that its free edge rests adjacent the body portion of said sheet.

32. A machine of the character described having in combination, means for advancing a sheet of material through said machine, means for positioning a pad on said sheet of 20 material as it is being passed through the machine, means for folding portions of said material adjacent said pad over said pad, means 25 for folding the folded portion of said material adjacent and beyond the pad over said pad, means whereby said pad is laid over so that its free edge rests adjacent the body portion of said sheet, and means for applying glue to 30 said sheet of material to hold said pad in its folded position.

33. A machine of the character described having in combination, means for advancing a sheet of material through said machine, 35 means for positioning a pad on said sheet of material as it is being passed through the machine, means for folding portions of said material adjacent said pad over said pad, means for folding the folded portion of said material 40 adjacent and beyond the pad over said pad, means whereby said pad is laid over so that its free edge rests adjacent the body portion of said sheet, grippers for holding said pad while it is being folded, and means for 45 releasing said grippers after the folding operation is completed.

34. A machine of the character described having in combination, means for advancing a sheet of material through said machine, 50 means for positioning a pad on said sheet of material as it is being passed through the machine, means for folding portions of said material adjacent said pad over said pad, means for folding the folded portion of said 55 material adjacent and beyond the pad over said pad, means whereby said pad is laid over so that its free edge rests adjacent the body portion of said sheet, means for scoring along the line of fold, means for holding said pad 60 while it is being folded, and means for holding the body portion of said sheet while said pad is being folded.

35. A machine of the character described having in combination, means for advancing 65 a sheet of material through said machine,

means for wrapping part of said sheet of material about a pad, means for projecting a sheet of regenerated cellulose onto the body portion of said sheet of material, and means for folding part of said body portion of the sheet of material over said sheet of regenerated cellulose. 70

36. A machine of the character described having in combination, means for advancing a sheet of material through said machine, 75 means for wrapping part of said sheet of material about a pad, means for projecting a sheet of regenerated cellulose onto the body portion of said sheet of material, means for folding part of said body portion of the sheet of material over said sheet of regenerated cellulose and means for scoring said body portion of the sheet of material along the line of fold. 80

37. A machine of the character described 85 having in combination, means for advancing a sheet of material through said machine, means for wrapping part of said sheet of material about a pad, means for projecting a sheet of regenerated cellulose onto the body 90 portion of said sheet of material, means for folding part of said body portion of the sheet of material over said sheet of regenerated cellulose, means for scoring said body portion of the sheet of material along the line of fold, 95 and means for holding the sheet of material while it is being scored and folded.

38. A machine of the character described having in combination, means for advancing a sheet of material through said machine, 100 means for wrapping part of said sheet of material about a pad, means for projecting a sheet of regenerated cellulose onto the body portion of said sheet of material, means for folding part of said body portion of the sheet 105 of material over said sheet of regenerated cellulose, and means for applying glue to said body portion of the sheet to hold said folded part in position.

39. A machine of the character described 110 having in combination, means for advancing a sheet of material through said machine, means for wrapping part of said sheet of material about a pad, means for projecting a sheet of regenerated cellulose onto the body 115 portion of said sheet of material, and means for folding part of said body portion of the sheet of material over said sheet of regenerated cellulose, said means comprising a pair of reciprocating slides, the lower one of which 120 is adapted to cooperate with a scorer and hold the sheet in position while the upper one folds said sheet.

40. A machine of the character described 125 having in combination, means for advancing a sheet of material through said machine, means for wrapping part of said sheet of material about a pad, means for projecting a sheet of regenerated cellulose onto the body portion of said sheet of material, means for 130

- 5 folding part of said body portion of the sheet of material over said sheet of regenerated cellulose, and means for giving the completely wrapped sachets a final pressing. 70
- 5 41. A machine of the character described having in combination, means for advancing a sheet of material through said machine, means for perforating a portion of said material as it is being passed through said machine, means for positioning a pad on said sheet of material, means for wrapping part of said sheet of material about said pad so that the perforated area of said sheet lies adjacent one of the sides of said pad, means for projecting a sheet of regenerated cellulose onto the body portion of said sheet of material, and means for folding part of said body portion of said sheet of material over said sheet of regenerated cellulose. 75
- 10 42. A machine of the character described having in combination, means for advancing a sheet of material through said machine, said sheet of material being so cut as to provide two flaps and a body portion, means for wrapping one of said flaps about an object, and means for folding the other of said flaps onto the body portion of said sheet. 80
- 15 43. A machine of the character described having in combination, means for advancing a sheet of material through said machine, said sheet of material being so cut as to provide two flaps and a body portion, means for perforating an area of one of said flaps, means for positioning an object over said perforated area, and means for wrapping said flap about said object. 85
- 20 44. A machine of the character described having in combination, means for advancing a sheet of material through said machine, said sheet of material being so cut as to provide two flaps and a body portion, means for positioning an object on one of said flaps, and means for wrapping said flap about said object. 90
- 25 45. A machine of the character described having in combination, means for advancing a sheet of material through said machine, said sheet of material being so cut as to provide two flaps and a body portion, means for positioning an object on one of said flaps, means for wrapping said flap about said object, means for folding the other of said flaps onto the body portion of said sheet, means for folding said wrapped part so that its edge lies adjacent the body portion of said sheet, and means for securing said wrapped part in position. 95
- 30 46. A machine of the character described having in combination, means for advancing a sheet of material through said machine, said sheet of material being so cut as to provide two flaps and a body portion, means for perforating an area of one of said flaps, means for positioning an object over said perforated area, and means for wrapping said flap about said object. 100
- 35 47. A machine of the character described having in combination, means for advancing a sheet of material through said machine, said sheet of material being so cut as to provide two flaps and a body portion, means for wrapping one of said flaps about an object, means for projecting another sheet of material onto said body portion of the first sheet, and means for securing said second-mentioned sheet in position. 105
- 40 48. A machine of the character described having in combination, means for advancing a sheet of material through said machine, said sheet of material being so cut as to provide two flaps and a body portion, means for folding one of said flaps onto the body portion of said sheet, means for positioning an object on the other flap, means for wrapping this flap about said object, means for projecting another sheet of material onto said body portion of the main sheet, and means for securing said second-mentioned sheet in position. 110
- 45 49. A machine of the character described having in combination, means for advancing a sheet of material through said machine, said sheet of material being so cut as to provide two flaps and a body portion, means for wrapping one of said flaps about an object, means for projecting another sheet of material onto said body portion of the first sheet, means for folding part of said body portion over said second sheet of material, and means for securing said folded part in position. 115
- 50 50. A machine of the character described having in combination, means for advancing a sheet of material through said machine, said sheet of material being so cut as to provide two flaps and a body portion, means for positioning an object on one of said flaps, means for wrapping said flap about said object, means for folding said wrapped part so that its edge lies adjacent the body portion of said sheet, means for projecting another sheet of material onto the body portion of the main sheet, and means for folding part of said body portion over said second sheet of material. 120
- 55 51. A machine of the character described having in combination, means for advancing a sheet of material through said machine, said sheet of material being so cut as to provide two flaps and a body portion, means for wrapping one of said flaps about an object, means for folding the other of said flaps onto the body portion of said sheet, means for projecting another sheet of material onto the body portion of said sheet, and means for folding the folded flap and body portion of 125
- 60 52. A machine of the character described having in combination, means for advancing a sheet of material through said machine, said sheet of material being so cut as to provide two flaps and a body portion, means for perforating an area of one of said flaps, means for positioning an object over said perforated area, and means for wrapping said 130

the sheet on which it rests over said second sheet.

52. A machine of the character described having in combination, means for advancing 5 a sheet of material through said machine, said sheet of material being so cut as to provide two flaps and a body portion, means for perforating an area of one of said flaps, means for positioning an object over said perforated 10 area, means for folding said flap about said object, means for folding the other of said flaps onto the body portion of said sheet, means for folding said wrapped portion so that its edge lies adjacent the body portion 15 of said sheet, means for projecting another sheet of material onto the body portion of said sheet, means for folding the folded flap and body portion of the sheet on which it rests over said second sheet, and means for 20 securing said folded parts in position.

53. A machine of the character described having in combination, means for advancing a sheet of material through said machine, said sheet of material being so cut as to provide 25 two flaps and a body portion, means for applying strips of glue to said sheet, means for wrapping one of said flaps about an object so that said strips of glue will hold said wrapped parts in position, means for projecting 30 a sheet of substantially impervious material onto said body portion so that said strips of glue will hold said impervious material in position, and means for folding part of said body portion over said impervious material.

54. A machine of the character described having in combination, means for advancing a sheet of material through said machine, means for wrapping part of said sheet of material about an object while passing 40 through said machine, means for feeding substantially impervious material from a web, and means for severing a strip from said web to associate said strip with a part of said first-mentioned sheet not wrapped 45 about the object.

55. A machine of the character described having in combination, means for advancing a sheet of material through said machine, means for wrapping part of said sheet of 50 material about an object while passing through said machine, means for feeding substantially impervious material from a web, means for imparting a latitudinal curve to said impervious material, and means for severing a strip of said material to associate 55 said strip with a part of said first-mentioned sheet not wrapped about the object.

56. A machine of the character described having in combination, means for advancing 60 a sheet of material through said machine, means for wrapping part of said sheet of material about an object while passing through said machine, means for feeding substantially impervious material from a web, 65 curved guide plates through which said im-

pervious material passes after leaving said web so as to impart a latitudinal curve to said impervious material to prevent it from buckling or curling, and means for severing a strip from said web after leaving said 70 curved guide plates so as to associate said strip with a part of said first-mentioned sheet not wrapped about the object.

57. A machine of the character described having in combination, means for advancing 75 a sheet of material through said machine, means for positioning an object on said sheet of material, means for wrapping part of said sheet about said object, means for sealing said sheet in position about said object, and means for associating a sheet of impervious material with part of said first-mentioned sheet not wrapped about said object.

58. A machine of the character described having in combination, means for intermittently advancing a sheet of material through said machine, means for perforating said sheet of material, means for applying adhesive to said sheet of material, means for positioning an object on said sheet of material, means for wrapping part of said sheet of material about said object, means for sealing said sheet in position about said object, and means for associating a sheet of impervious material with a part of said first-mentioned sheet not wrapped about said object, some of the foregoing operations being performed while said first-mentioned sheet is 80 at rest and others being performed while 90 said sheet is in motion.

59. A machine of the character described having in combination, means for intermittently advancing a sheet of material through said machine, a plurality of segments having their peripheries in staggered relation to each other for applying strips of glue to said sheet while it is in motion through the machine, means for providing an even distribution of glue to said segments, and means 100 for wrapping part of said sheet of material about an object.
